(57) **CLAIM**

The ornamental design for a sink deck, as shown and described.

DESCRIPTION

In a preferred embodiment, the nature of this product is as a plumbing fixture, preferably a kitchen sink or portion thereof.

FIG. 1 is a right, top, front perspective view of an embodiment of my new design, in the form of a deck for a sink;

FIG. 2 is a top plan view thereof;

FIG. 3 is a front elevational view thereof, the rear elevational view thereof being a mirror image of the front view shown;

FIG. 4 is a right side elevational view thereof;

FIG. 5 is a left side elevational view thereof;

FIG. 6 is a bottom plan view thereof;

FIG. 7 is a partial sectional view taken along line 7—7 of FIG. 2; and,

FIG. 8 is a left, top, front perspective view of another embodiment a sink deck according to my new design, the top plan, front elevational, rear elevational, right side elevational, left side elevational and bottom plan views being mirror images of those disclosed in FIGS. 1-6 and the accompanying description.

The broken line representations of openings, such as faucet mount openings and/or drain openings, in FIGS. 1-6 and 8, of underside deck structure in FIG. 6, and one or two basins in FIGS. 1-6 are for the purpose of illustration only, and form no part of the claimed design.
